UNITED STATES PATENT OFFICE.

PAUL S. HALL, OF AUSTIN, MINNESOTA, ASSIGNOR OF ONE-HALF TO GUSTAVE J. VOSS,
OF AUSTIN, MINNESOTA.

WHEEL-TIRE.

1,177,514.

Specification of Letters Patent. Patented Mar. 28, 1916.

Application filed June 22, 1915. Serial No. 35,604.

To all whom it may concern:

Be it known that I, PAUL S. HALL, a citizen of the United States, residing at Austin, in the county of Mower and State of Minnesota, have invented new and useful Improvements in Wheel-Tires, of which the following is a specification.

The invention relates to an improvement in tires, particularly to a resilient tire involving the use of spring elements for the supporting means.

The improved tire embodies a construction involving essentially a means for securing to the felly of the wheel a holding member of particular formation for removably supporting a series of spring forming elements and also for holding in place the fabric casing; the spring forming elements being constructed to provide a reinforce of the casing at the wear point.

The invention in the preferred form of details will be described in the following specification, reference being had particularly to the accompanying drawings, in which:

Figure 1 is a longitudinal sectional view through a portion of the improved tire; Fig. 2 is a transverse view through the same; Fig. 3 is a perspective view of one section of the clamping member; Fig. 4 is a perspective view of one of the spring elements; Fig. 5 is a perspective view of one of the stop abutments; Fig. 6 is a broken perspective view showing the connection of the clamp member to the felly and the connection of the springs to the clamp member. Fig. 7 is a view in elevation of the completed wheel.

In carrying out the invention I provide what is termed the clamp member comprising double sections of annular formation adapted to fit more or less closely to the felly 1 of the wheel. The sections 2 forming the clamp member each include a flat plate like portion 3 approximating in width half the width of the felly, which plate member is at its inner edge formed in a return bend upon itself to form a clamping lip 4. The outer edge of the section is outwardly turned to provide a flange 5. Securing plates 7 are riveted to the clamp member, being secured to both sections and having an extension 8 adapted to be turned in against the felly and to be secured thereto by a bolt 9. One of the securing plates

may, if desired, be of materially greater width circumferentially of the felly than the others, and the overlying or meeting ends of the clamp sections secured thereto. It is of course to be understood that any desirable number of securing plates are used and that preferably the felly is recessed to receive them as shown at 10.

Carried by the clamping member are spring forming elements including spring sections 11 bent into form approximating that of the completed tire with their free ends at the inner portion. Diametrically opposite the free ends the spring section is formed to provide an inwardly offset portion 12 to which there is removably secured a stop abutment. The latter comprises a metallic strip bent to form a loop end 13 to snugly embrace the portion 12 of the spring element, the stop abutment has a projection 14 which extends within the spring section and terminates at its inner end some distance outwardly beyond the free edges of the spring section, the function of this stop being to prevent, through load strain, excessive spreading of the spring element, as will be obvious.

After the clamping member is secured in place as described the spring elements are applied by inserting the free ends of each of said elements beneath the lips 4 of the clamping member sections, this operation holding the spring elements in place, there is provided a sufficient number of such elements to encircle the wheel and form in effect a tire-like structure. A casing 15 of suitable fabric is arranged to envelop the spring elements, the offset portions 12 forming a channel circumferentially of the wheel to receive a thickened portion 16 interiorly of the casing which provides additional material at the wear points, and at the same time serves to center the spring elements and hold them in alinement. The edges of the casing 15 are provided with loop terminals 17 which are transversely cut to provide what may be termed a series of independent loops. A wire 18 is passed through the loops of each side of the casing and extends around the clamp member immediately adjacent the flange 5, the ends of the wire being connected by a turn-buckle 19 for tightening, the flange 5 being interrupted to permit the position of the turn-buckle as shown. By dividing the loop of the casing 110

as described the application and removal of the casing is facilitated.

In the improved tire it will be obvious that the load strain is resisted by the spring elements, and that any one or more of such elements may be conveniently removed from the clamping member when it is necessary to replace them by new ones. The improved tire is as effectively resilient as the pneumatic tire while at the same time obviating the use of air with its consequent disadvantages. The spring elements are made of spring material and may be of a size to produce a tire of required dimension, the co-operating parts being obviously varied in size to accommodate the increased dimensions of the spring elements.

What is claimed is:

1. A wheel tire including a clamping member made up of separable sections adapted to be disposed circumferentially of the wheel, the inner edge of each section being returned upon itself to form a clamping lip, the outer edge of each section being outwardly turned to form a flange, a series of independent spring elements having their ends engaged beneath the lips of both sections, and a casing encircling the spring elements, and held within the outer flanges.
2. A wheel tire including a clamping member, a series of independent spring elements separately and removably engaging

the clamping member and means carried by each element to engage the clamping member and limit the movement of such element under load strain.

3. A wheel tire including a clamping member, a series of independent spring elements separately and removably engaging the clamping member and means carried by each element to engage the clamping member and limit the movement of such element under load strain, each element being formed to provide a depression and a casing inclosing the elements and having an enlarged portion to fit the depression.

4. A wheel tire including a clamping member disposed circumferentially of the wheel, a series of transversely arranged spring elements separately and removably engaging the clamping member, said elements conforming in sectional contour to that of a tire casing, and a stop abutment removably and frictionally engaging each spring element and projecting within the same, the free terminal of the abutment being normally in spaced relation to the clamping member.

In testimony whereof I affix my signature in presence of two witnesses:

PAUL S. HALL.
